US00D804903S

(12) **United States Design Patent** (10) Patent No.: **US D804,903 S**
Mason et al. (45) Date of Patent: **** Dec. 12, 2017**

(54) **STRAW LID**

(71) Applicant: **Igloo Products Corp.**, Katy, TX (US)

(72) Inventors: **John Mason**, Bridgewater, MA (US);
Brandon Stroud, Smyrna, GA (US)

(73) Assignee: **Igloo Products Corp.**, Katy, TX (US)

(**) Term: **15 Years**

(21) Appl. No.: **29/557,001**

(22) Filed: **Mar. 4, 2016**

(51) LOC (10) Cl. **07-01**

(52) U.S. Cl.

USPC **D7/510**

(58) **Field of Classification Search**

(57) **CLAIM**

The ornamental design for a straw lid, as shown and described.

DESCRIPTION

FIG. 1 is a perspective view of a first embodiment of a straw lid in a closed state, in use condition, showing our new design;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof;

FIG. 8 is a perspective view of a second embodiment of a straw lid in an open state, in use condition;

FIG. 9 is a front view thereof;

FIG. 10 is a back view thereof;

FIG. 11 is a left view thereof;

FIG. 12 is a right view thereof;

FIG. 13 is a top view thereof;

FIG. 14 is a bottom view thereof;

FIG. 15 is a perspective view of a third embodiment of a straw lid in a closed state, in use condition;

FIG. 16 is a front view thereof;

FIG. 17 is a back view thereof;

FIG. 18 is a left view thereof;

FIG. 19 is a right view thereof;

FIG. 20 is a top view thereof;

FIG. 21 is a bottom view thereof;

FIG. 22 is a perspective view of a fourth embodiment of a straw lid in an open state, in use condition;

FIG. 23 is a front view thereof;

FIG. 24 is a back view thereof;

FIG. 25 is a left view thereof;

FIG. 26 is a right view thereof;

FIG. 27 is a top view thereof; and,

FIG. 28 is a bottom view thereof.

The broken lines in the drawing views represent unclaimed portions of a straw lid, which are included for the purpose of illustrating unclaimed environment only, and forms no part of the claimed design.

1 Claim, 28 Drawing Sheets
